Primary Examiner — Mitchell I. Siegel*(74) Attorney, Agent, or Firm* — ScienBiziP, P.C.(57) **CLAIM**

The ornamental design for a swing seat, as shown and described.

DESCRIPTION

FIG. 1 is a front, right, and top perspective view of a swing seat, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken away portions in the drawings indicate the appearance of any portion of the article between the break lines forms no part of the claimed design.

1 Claim, 8 Drawing Sheets(56)
